UNITED STATES PATENT OFFICE.

OSCAR F. BERGQUIST, OF FORSYTH, MICHIGAN.

FOOT-PLATE ATTACHMENT FOR SPADES OR THE LIKE.

Application filed October 6, 1925. Serial No. 60,811.

The present invention relates to a foot-plate for use in connection with spades, shovels, pitchforks, and the like, and aims to provide a novel and improved device of this character which can be conveniently associated with a tool of the above indicated character for presenting a relatively large surface for engagement with the foot so as to eliminate the breaking of the arch of a shoe and the injuring of a foot caused by engagement with the thin edge of a spade or the like.

A further object of the invention is the provision of a footplate having means for permitting the foot engaging surface thereof to be swung at various angles so as to be in engagement with a relatively large surface of the shoe of the user, independent of the angle the pressure is applied from, thus causing the efficient operation of the tool at all times.

It is also an object of the invention to provide a device of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein:

Figure 1 is a front elevation of a spade showing my improved device applied thereto,

Figure 2 is a fragmentary edge view of a spade, showing the device thereon, and

Figure 3 is a vertical section taken on line 3-3 of Figure 1, showing the device removed from the spade.

Referring to the drawing, the numeral 5 designates a spade having a handle 6 and earth engaging blade 7. Most spades are slightly reinforced at the upper edge of the blade, as at 8, for slightly increasing the width of the blade at its upper edge where the foot of the user is placed for forcing the blade of the spade into the soil. In order to increase the surface at the upper edge of the blade 7, I have provided my improved footplate.

In carrying out my invention, the numeral

10 indicates an inverted U-shaped bracket, the opposite depending legs 11 and 12 thereof being arranged for engaging opposite sides of the blade 7 of the spade at the upper portion thereof adjacent the reinforcement 8. The legs 11 and 12 conform to the general configuration of the blade of the spade and each is provided with an opening 13 through which a rivet or bolt 14 is passed which also extends through an opening provided in the blade 7 for securing the bracket to the blade. The legs 11 and 12 are formed so as to engage each other adjacent the bight portion of the inverted U-shaped bracket, as at 15, and are riveted or secured together in any well known manner, as shown by the numeral 16. The bight portion of the U-shaped member is arranged in circular formation in cross section as shown at 17 for receiving therein a bolt 18.

Arranged above the bight portion of the inverted U-shaped bracket 10 is a slightly arcuate plate 19 which has the upper surface thereof roughened or serrated, as at 20, for eliminating to a great extent the danger of the foot of a user from sliding thereoff. Secured to the under surface of the plate 19 by means of rivets 21 is a pair of angled members 22, which have one angled portion 85 thereof depending therefrom so as to engage the opposite side edges of the circular portion 17 of the inverted U-shaped bracket. The depending portions of the angled members 22 have openings therein through which 90 the opposite ends of the bolt 18 extend so as to pivotally connect the plate 19 to the bracket 10. The bolt 18 has a head on one end thereof and a nut on the opposite end thereof so as to cause a slight binding action 95 on the opposite edges of the bracket for yieldably holding the plate against easy swinging movement with relation to the bracket.

With my improved footplate attached to a spade or the like by means of the rivet 14, the user may apply pressure on the blade of the spade from any angle, the pivotal connection of the foot engaging plate with the spade permitting the pressure to be applied 100 from all downward angles. It can thus be seen that a relatively large surface is always in engagement with the shoe of the user, thus eliminating danger of the user injuring his foot by excessive pressure or the breaking 110 of the arch of his shoe, as often occurs while using spades without my improved

attachment. As the upper surface of the plate 19 is roughened and slightly arcuate, the danger of the foot of the user slipping thereoff is also eliminated, so as to provide 5 an attachment for spades or the like which will be thoroughly efficient for the purpose intended. By removing the bolt 14 the attachment may be readily disconnected from the spade and attached to another tool if so 10 desired.

Having thus described my invention, what I claim as new is:

1. A foot engaging member in combination with a tool comprising a bracket, a foot 15 engaging plate, a pair of angled members secured to said plate and arranged at each side of said bracket, and a bolt extending through said angled members and through said bracket for pivotally connecting said 20 plate to said bracket.

2. A foot engaging member in combination with a tool comprising an inverted U-shaped bracket adapted to engage over the soil working element of the tool, said 25 bracket having a cylindrical opening formed in the upper portion thereof, a foot engaging plate, angled members secured to said plate and depending therefrom, and a bolt extending through said angled members and 30 through the cylindrical opening in said

bracket for pivotally connecting said plate to said bracket.

3. A foot engaging member in combination with a tool comprising an inverted U-shaped bracket, the opposite legs of said 35 U-shaped bracket being adapted to engage the opposite sides of the soil working element of the tool, means for securing said opposite legs of said bracket to the tool, said U-shaped bracket being formed so that the 40 opposite leg portions thereof engage each other adjacent the upper portion of the bracket, means for securing said engaging portions of said legs together, said U-shaped bracket having a cylindrical opening formed 45 therein above the engaging portions of the legs, a foot engaging plate, a pair of angled members each having one side thereof secured to said plate while the other sides of said angled members extend downwardly on 50 each side of said bracket at said cylindrical opening, and a bolt extended through said cylindrical opening of said bracket and through the depending sides of said angled members for pivotally connecting said plate 55 to said bracket.

In testimony whereof, I have affixed my signature.

OSCAR F. BERGQUIST.
